United States Patent Office

Des. 228,766

Patented Oct. 23, 1973

228,766

GAS BURNER

Charles E. Stohrer, Jr., Hickory Hills, Ill., assignor to
Harper-Wyman Company, Hinsdale, Ill.

Filed Dec. 8, 1971, Ser. No. 206,238

Term of patent 14 years

Int. Cl. D23—03

U.S. Cl. D23—129

FIG. 1

FIG. 2

FIG. 3

FIG. 4

FIG. 1 is a top perspective view of a gas burner embodying my new design;

FIG. 2 is a side elevational view of the gas burner;

FIG. 3 is a top view of the gas burner; and

FIG. 4 is a bottom view of the gas burner.

The gas burner is similar in appearance from all sides. I claim:

The ornamental design for a gas burner, substantially as shown and described.
